UNITED STATES PATENT OFFICE

FLETCHER J. MCQUEEN, OF OCALA, FLORIDA, ASSIGNOR OF ONE-HALF
TO JAMES N. STROBHar, OF SAME PLACE.

CAR-COUPING.

SPECIFICATION forming part of Letters Patent No. 379,177, dated March 6, 1888.

Application filed August 2, 1887. Serial No. 245,964. (No model.)

To all whom it may concern:

Be it known that I, FLETCHER J. MCQUEEN, a citizen of the United States, residing at Ocala, in the county of Marion and State of Florida, 5 have invented new and useful Improvements in Car-Couplings, of which the following is a specification.

My invention relates to that class of car-couplings comprising a draw-bar having a 10 hooked pin and an oscillating link operated by rack-and-pinion gearing, so that said link can be readily engaged with or disengaged from the hooked pin of the opposite draw-bar; and the invention consists in the construction 15 and combination of devices hereinafter described and claimed.

In the annexed drawings, illustrating the invention, Figure 1 is a side elevation of my improved car-coupling. Fig. 2 is a front elevation of the same with coupling-link lowered. Fig. 3 is a vertical longitudinal section of one draw-bar provided with my improved coupling devices. Fig. 4 is a plan of the same. Fig. 5 is a view of the hooked coupling-pin.

Referring to the drawings, the letter A designates the body of a freight-car, and B an ordinary open-mouth draw-bar supported beneath the car in any suitable or well-known manner. In the center of the draw-bar, back 30 of the abutment *a*, is a longitudinal slot, *b*, that extends entirely through the draw-bar from top to bottom. A shaft, *c*, is journaled transversely in the draw-bar through the longitudinal slot *b*, and on said shaft a pinion, *C*, is securely mounted, as shown. The shaft *c* 35 is securely mounted, as shown. The shaft *c* also carries a coupling link or bail, *D*, which is securely fastened to the projecting ends of said shaft on each side of the draw-bar.

The shaft *c* and attached pinion *C* are rotated to oscillate the link *D* by means of a rack-bar, *E*, which is adapted to move vertically in the rear end of the slot *b*, and thus raise or lower the link, as required. This rack-bar *E* has shoulders *d d* at or near its ends to limit 45 its movements.

To the upper end of the rack-bar *E* is pivoted a lever, *F*, which is also pivoted to the end of the car and extends to one side to enable the coupling to be operated without incurring any necessity of passing between the cars.

The coupling link or bail *D* of each draw-bar is adapted to engage a hooked pin, *H*, carried by the opposite draw-bar, only one link and pin, however, being employed at the 55 same time, though the others are ready for use in case of need. The pin *H* is held in openings *e f*, formed in the mouth of the draw-bar at top and bottom, and the upper opening, *f*, is squared to fit a correspondingly-squared 60 portion, *g*, of the pin *H*, so as to prevent it from turning in the draw-bar when the link *D* is engaged with the rearwardly-curved hook *h*, that is formed on the upper end of the pin.

By reference to Fig. 1 it will be seen that 65 the draw-bars, either of the same or varying height, can be securely coupled by the engagement of the link *D* of one draw-bar with the hooked pin *H* of the opposite draw-bar; and it will be understood that the weight of 70 the link, together with the weight of the levers *F G*, is sufficient to hold the link down to its engagement with the hooked pin, so that there will be no liability of accidental uncoupling through the jolting of the cars or by the 75 concussion of contacting draw-bars in stopping or starting.

The arrangement of the pinion *C* and rack-bar *E* in a central longitudinal slot, *b*, formed in the body of the draw-bar, serves to protect 80 said pinion and rack from any liability of injury that would be incurred by locating them on the outside of the draw-bar.

It will be observed that this car-coupling mechanism is of such character that it will not 85 interfere with the use of the ordinary link for connecting with another draw-bar having the ordinary link-and-pin coupling, as it is only necessary to remove the pin *H* to admit an ordinary link into the mouth of the draw-bar. 90 It will also be seen that with the ordinary link the bail *D* can be used as a link-raiser, if desired, so as to facilitate the coupling of cars having draw-bars of different heights when one is provided with the ordinary link-and-pin coupling. 95

What I claim as my invention is—

1. In a car-coupling, the combination of a draw-bar having a vertical longitudinal slot, a shaft journaled transversely through said slot, a pinion secured to said shaft within the slot, a link fastened to the outer ends of the

shaft, and a vertically-movable rack-bar located in the rear end of the slot and meshing with the pinion to operate the link and engage it with or disengage it from a hooked pin on the opposite draw-bar, substantially as described.

2. The combination of the open-mouthed draw-bar B, having a vertical longitudinal slot, b, the shaft c, carrying an oscillating link, D, the hooked pin H, having a squared portion, g, to prevent it from turning, the pinion C, secured to the shaft c within the slot b, and the vertically-movable rack-bar E, to operate the pinion C and link D, whereby the link can be engaged with or disengaged from the hooked pin of the opposite draw-bar, or the pins of said draw-bar be connected by an ordinary link, substantially as described.

3. The combination of a draw-bar having a vertical longitudinal slot, b, a shaft, c, journaled transversely through said slot, the pinion C, fixed to said shaft within the slot, the link D, securely mounted on the shaft c, the rack-bar E, located in the slot to engage the pinion, and the levers F G, connected with the rack-bar and adapted by their weight to throw the link down, substantially as described.

In testimony whereof I affix my signature in presence of two witnesses.

F. J. McQUEEN.
